TOY FARMHOUSE

Frank C. Fusco, Monroe, N.Y., assignor to Louis Marx & Co. Inc.

Filed Apr. 19, 1971, Ser. No. 135,260

Term of patent 14 years

Int. Cl. D21—01

U.S. Cl. D34—15

FIG. 1

FIG. 2

FIG. 3

FIG. 4

FIG. 5

FIG. 1 is a top plan view of a toy farmhouse in accordance with my new design;

FIG. 2 is a side elevation view thereof;

FIG. 3 is a view similar to FIG. 2 showing the opposite side thereof;

FIG. 4 is a view of one end thereof; and

FIG. 5 is a view of the opposite end thereof.

I claim:

The ornamental design for a toy farmhouse, as shown.
